MARIUS SERFAUSTINI, OF PARIS, FRANCE.

FOLDING TABLE.

Application filed February 3, 1922. Serial No. 533,897.

To all whom it may concern:

Be it known that I, MARIUS SERFAUSTINI, of 9 Rue des Boulanger, Paris, France, have invented a Folding Table, of which the following is a full, clear, and exact description.

The present invention relates to a folding table of seven lengths, more especially adapted for wall-paper hangers.

10 It has for object to replace the tables, which paper hangers mount on trestles for executing their work, tables which are heavy, inconvenient, cumbersome, not easily carried about and are of one length only.

15 The invention consists of a table formed of sections hinged together and having hinged legs to fold in the sections, the sections when folded forming a box for the storage of tools and other articles.

20 The invention also consists in providing the table with a plurality of hinged leaves detachably secured thereto and which when removed are adapted to be stored in the sections of the table.

25 The invention further consists in the particular construction and arrangement of parts as hereinafter described and pointed out in the claims.

This invention will be described hereafter, 30 by way of example only, with reference to the accompanying drawing, in which:

Fig. 1 is a front view of the improved table, folded.

Fig. 2 is an end view.

35 Fig. 3 shows in elevation, the table extended, as well as its leaves.

Fig. 4 is a plan view corresponding to Fig. 3.

Fig. 5 is an end view.

40 Fig. 6 shows the table from underneath, the table being opened but not extended.

Fig. 7 is a cross-section of the table opened but not extended, the section being made on line A—A of Fig. 3.

45 Fig. 8 is a cross-section of the table opened with the legs extended, this section being made on line B—B of Fig. 3.

Fig. 9 is a longitudinal section of a part of the table showing the legs and the leaves 50 extended, this section being made on line C—C of Fig. 4.

Fig. 10 is a cross-section of the table folded.

As will be seen in the drawing, Fig. 1, 55 this table, when folded, has the aspect of a

thin and long rectangular box in the form of a tray comprising two equal parts *a a*, *c c* arranged side by side, connected and articulated, by hinges, longitudinally.

The closed box is characterized by a double flange formed by the flat parts *a a* provided on the framing *c c*. This double flange exists on the three sides of the box where there are no hinges; it is adapted to give strength to the box and to support the outer devices when the table is opened, whilst the side, having hinges, of the framing *c c* is on a level with the flat parts *a a*. The hinges are indicated by the reference letter *b* (Fig. 2). The flanges *a a* (Fig. 2) are surrounded by a metallic band to prevent damages when the table is placed up on end on the ground.

This box is also provided with a shoulder-belt *u* which allows it to be carried over the shoulder, see Figs. 1 and 2.

All the accessories are placed within the box, as indicated Fig. 6, showing the box opened. In this box *l l* are the leaves with the sections folded one on the other; *q* is a rule; *r* is a strip of zinc in the form of an angle-iron (these latter are placed one on the other); *s* are two brackets; *d* are two stop pins, the whole is removably held in place by swivels *h*. The net *j*, connected to the four legs of the table, rests on these accessories. The box also contains an auxiliary leaf *v* (Fig. 6). This leaf serves to widen the table on nearly its entire length.

The four folding legs *f*, independent from one another, have the shape of a square and are connected to the table by hinges *g*, Fig. 6; when they are folded, they are removably maintained by the swivels *h*.

The letter *n* (Fig. 6) indicates the position of rest and the shape of the four supports of the leaves; these supports are made of a solid tube of steel without soldering; they are provided with a collar *n¹* in which falls a kind of spring catch *p*; at the other end the supports are engaged in slideways *o* secured to the table which removably hold them in place.

To lengthen the table, the spring catch is released from the collar *n¹*, then the support is made to slide towards the exterior along the slideways *o*, this displacement of the support, until the pin *n²* abuts against the slideway *o*, stops the forward movement of this support (Fig. 9).

When the box is closed, as shown in Figs. 1 and 2, and the table is to be formed, the two parts constituting this box are opened until the two faces *a a*, coming in the same plane thus form a single board which is rendered rigid by two pins *d* (one in each end of the board). Each pin *d* is engaged in two slideways *e* which are secured on the transverse part of the framing, see Fig. 5 10 which shows the two ends of the pin *d* projecting, beyond the two slideways *e*.

With this rigid board, which is twice the size of the box, the table is formed by extending the legs *f*. These legs are maintained rigidly extended by means of struts *i* 15 which are engaged on retaining devices *i'*, see Figs. 6, 3 and 9.

During this operation, the net *j* which is connected to the four legs *f*, stretches by itself and remains maintained by suspension ties *k*, see Fig. 3.

The table thus set up, holds the accessories underneath and they are taken out when needed.

25 If it is necessary to increase the length of this table, the leaves *l* are put in position by engaging their hooks *g*, Fig. 9, in recesses *m*¹ provided in the ends of the table and by strengthening them by means of the supports *n* above mentioned, see Figs. 3 and 9; these supports are made to slide, from underneath the table, towards the exterior until they are stopped by the pins *n*², see Fig. 9.

35 There are two leaves *l*, Fig. 4, (one at each end of the table) and each is in three sections that is to say, in three small boards, placed across the table; they are connected together and jointed by means of hinges. 40 The outside small board is connected to the central one by means of two hinges placed underneath, so as to be able to fold it downwards, only in case the table should be too long. The middle small board is connected 45 to the third one by means of pin hinges, placed (one at each end) in the thickness of the two small boards; moreover these two small boards are rendered rigid by an assemblage in the form of a floor-board. 50 The third small board is provided with two fixed flat hooks *m* which removably retain it on the body of the table, and the whole forms a single rigid plane.

These sections of leaves, thus combined 55 form only a single rigid leaf when they are extended and overhung from underneath by the two supports made of tubes of steel *n*, that is to say, that they cannot be folded back upwardly; but if it is desired to diminish the length of the table it is simply necessary to push, the supports *n* internally, Figs. 3 and 9, and to fold back downwardly, the small board or boards not utilized, whilst the other small boards remaining 60 rigidly horizontal form a single plane with

the body of the table. This arrangement permits of giving the table seven different lengths or of simply doubling its length.

Finally the brackets *s* are then placed in position if necessary, by engaging them in recess *t* adapted to receive them. On these brackets, the rule *q* is placed (Fig. 4) which is thus out of the way of the paper spread out on the table, so that it is always ready to be used. 75

It is to be understood that the strip of zinc *r*, may be of the length of the rule and when not in use is in one of the sections and the rule rests therein and the two are secured in the section, as shown in Figure 6. When the rule and strip are to be used, they are placed on the brackets *s* on the front side of the table, as indicated in Fig. 4. This strip of zinc serves as a flange for margining the paper and for cutting out the friezes. The paper to be margined is drawn on the flange, the rule is placed on the cutting line, and cut with a sharp blade guided by the rule, then the rule *q* is replaced on the brackets *s*, as indicated 80 85 Fig. 4.

This table is then folded, when necessary, by proceeding in the reverse order that has just been indicated for its extension, to form, again, the box above stated. 90

Claims:

1. A folding table comprising two tray-like sections hinged together at their longitudinal edges to fold one upon the other to form a box, means for locking the sections in position, legs hinged to the sections to fold them into the same, means for locking the legs in the sections, two sets of hinged leaves, each set having a detachable interlocking engagement with one end of the sections, the leaves being adapted to be placed in a section when the sections are folded, a pair of rods slidably mounted in each section and adapted to be extended beyond the ends of the sections to support the said leaves, and locking means in the sections for securing the leaves and other articles in the sections. 100 105 110

2. A folding table, comprising two tray-like sections hinged together at their longitudinal edges to fold one upon the other to form a box, a leg hinged to each end of each section to fold into the same, two sets of hinged leaves, the leaves of each set being hinged together and of a length equal to the combined width of the sections, each set of leaves having a detachable interlocking connection with an end of the sections, and adapted when not in use and folded to be placed in one of the sections, means for locking the leaves in the sections, and a rod slidably mounted in each end of each section and adapted to be extended beyond the ends of the sections to support said leaves when in use. 115 120 125 130

3. A folding table comprising two tray-like sections hinged together at their longitudinal edges to fold one upon the other to form a box, two sets of leaves, the leaves of each set being hinged together and of a length equal to the combined width of the two sections, the leaves of the sets being adapted to be folded one upon the other and placed in one of the sections with the sets in alignment with each other, means for

securing the sets of leaves in the sections, means for detachably connecting the sets of leaves with the ends of the sections, and means for supporting the leaves of the sets of leaves in a horizontal position when connected with the ends of the sections. 15

The foregoing specification of my "folding table", signed by me this 19th day of January, 1922.

MARIUS SERFAUSTINI.
